UNITED STATES PATENT OFFICE

OTTO ZAHN, OF HANAU-ON-THE-MAIN, GERMANY

CONNECTION APPARATUS FOR THE WIRES OF HEAD RECEIVERS FOR BROADCASTING

Application filed December 1, 1928, Serial No. 323,157, and in Germany June 21, 1928.

This invention relates to a connection apparatus for the wires of head receivers for broadcasting designed to permit dancing to broadcasted dancing music when there is no 5 loud speaker or when a loud speaker is not to be used, in order not to disturb persons in the room who do not want to dance.

An embodiment is illustrated by way of example in the accompanying drawing in—
10 Fig. 1 in side elevation;

Fig. 2 is a perspective view showing the apparatus used by two people dancing.

The apparatus consists of a box *a* of insulating material comprising two sleeves for 15 connecting to a receiving apparatus. From this box *a* projects in downward direction a sleeve *c* in insulating material in which a bolt *d* is mounted which is connected to one of the sleeves *b*. On the ball-shaped lower 20 end of bolt *d* a sleeve *e* is loosely mounted so that it can rotate around said ball-shaped end. This sleeve *d* is designed to receive a contact plug *f* for the receiver-wires *g*. The second contact plug *h* of the receiver-wires 25 is inserted into a sleeve *k* suspended on a ring *i*. The ring *i* is attached to a frame *m*, loosely resting on the collar *n* of a metal sleeve *o*. This metal sleeve *o* is pushed over the sleeve 30 *c* of insulation material and connected to the second contact sleeve *b*.

Owing to this fixation the wires *g*, to the ends of which head receivers are attached, cannot be twisted together when the persons 35 wearing the head receivers are dancing.

Fig. 2 shows how the apparatus is used.

In order to prevent short-circuit the ends of the wires *g* are of different length so that the pressure screws in the contact plugs cannot touch each other.

40 I claim:

An apparatus for connecting to the main line the wires of head receivers for broadcasting, comprising in combination a box, two contact sleeves in said box adapted to be 45 connected to the main line, a sleeve of insulating material downwardly projecting from said box, a metal pin in said insulation sleeve connected to one of said contact sleeves in said box, a ball-shaped head on the lower end 50 of said pin, a plug sleeve loosely mounted on

said ball-shaped head so that it can rotate around the same adapted to receive a contact plug from the head receivers, a metal sleeve on said insulation sleeve connected to the second contact sleeve of said box, a collar 55 on said metal sleeve, a metal frame loosely resting on said collar, a ring attached to said frame, and a contact sleeve suspended on said ring designed to receive a contact plug of the other wires of the head receivers.

In testimony whereof I affix my signature.

OTTO ZAHN.
